UNITED STATES PATENT OFFICE

2,481,751

VARIABLE THRUST AND REVERSING
PROPELLER

Jerome B. James, Emigrant Gap, Calif.

Application June 14, 1946, Serial No. 676,727

4 Claims. (Cl. 170—160.52)

1

The present invention relates to marine propeller drives and is more particularly concerned with a propeller adjustable to perform the dual functions of forward and reverse drives.

The primary object of the invention is to provide a propeller of the character referred to which can be readily changed over from a forward thrust to a reverse thrust.

Another object of the invention is to provide a propeller of the character referred to which is controlled automatically as well as manually.

A further object of the invention is to provide a propeller with integral forward-thrust and reverse-thrust blades which are under selective control.

Still another object of the invention is to provide a double-duty propeller blade which is adjustable for the purpose of stowing one blade away when the other one is in use.

With the foregoing and other objects and advantages in view the invention consists of the novel construction and arrangement of parts hereinafter described and claimed.

In the accompanying drawings illustrating the preferred embodiment of the invention;

Figure 1 is a side elevation of a propeller hub and blades constructed in accordance with the invention.

Figure 2 is a longitudinal section thereof.

Figure 3 is a transverse section of the hub on line 3—3 of Figure 1.

Like numerals, as used in the description and drawings, designate the same structural parts.

The body 10 of the propeller hub is tubular in general and open at the rear, where the closure is a screw cap 11. This is provided with vents 12.

The propeller shaft 13 is tubular and preferably integral with the hub.

Two diametrically disposed rectangular apertures 14 are provided in the hub for reception of the bosses 15 of dual propellers. The bosses are mounted in said apertures to pivot on transverse pins 16.

Each propeller consists of two integral blades 17 and 18 positioned relatively at an angle of approximately 90°. If desired, more than two propeller units may be employed, in which case additional recesses 14 and 14a will be provided.

The blade 17 designed for forward thrust, is longer in area than 18, and located rearwardly of the blade 18, which is designed for a reverse or forward thrust. Apertures 14 are constructed to allow the blades to be dropped down close to axial parallelism with the propeller shaft 13, so that whenever the blade 18 is not in use it can

2

be made to flush with the hub 10, as illustrated in Figure 1.

Projecting laterally from the bosses of the propellers and approximately at an angle of 90° are lugs 19 with the outer edges curved to serve as cams which bear against a cup-shaped member 20, which is axially reciprocable within the hub 10 and serves to contain one end of a coil spring 21. The other end of the spring bears against the interior surface of the hub cap 11.

A longitudinal control rod 22 is secured fast to the center of the closed end of member 20, and extends forwardly through the tubular propeller shaft 13 to a point of control, located as desired. The function of the rod 22 is to drop either blade of the propeller as desired, and it may be operated by levers or other means, in the forward housing of the gear case, with controls in proximity to the motor head. As the closed end of member 20 is perpendicular to the axis of rotation the blades are caused to operate evenly and equally, thus eliminating a possible source of vibration.

When the two forward-thrust blades are in operating position, they are perpendicular to the axis of rotation, thereby presenting maximum areas with the water. At the same time the reverse thrust blades are flush with the surface of the hub 10, a recess 14a extending forwardly from aperture 14 for this purpose.

When the blade 18 is in operating position, the blade 17 is lowered to close proximity with the surface of the hub.

Control of the cams on bosses 15 is attained in several ways. Two are here explained. The inner end of control rod 22 may be suitably linked directly to the cam shaped lugs 19 to allow shifting positively from maximum forward position to maximum reverse or to an intermediate position; or the cam construction hereinbefore described may be used. In the latter case action of the coil spring 21 tends to maintain the blades in reverse thrust position but the torque presented will cause the blades to shift into forward thrust position, due to centrifugal force and the greater thrust area of the blades 17. Such action becomes automatic by control of the propeller speed but can be controlled by use of control rod 22.

It will thus be obvious that the propeller blades can be held in reverse or in an intermediate position for reduced boat speed.

As different embodiments may be made of this inventive concept and modifications may be made in the embodiment hereinbefore shown and de-

scribed, it will be understood that the matter herein is to be interpreted as illustrative merely, and not in a limiting sense.

What I claim is:

1. A propeller comprising a tubular hub, two integral blades having a common boss with a cam shoulder, said boss being pivotally mounted in said hub, said blades being set relatively to each other at substantially a right angle and with relative pitches to produce in one a forward thrusting action and in the other a reverse thrusting action, an axially reciprocable rod to operate said cam to pivot said blades alternately out of operative position, and resilient means to produce axial tension on said operating rod.

2. A propeller comprising a tubular hub, a tubular powered shaft secured to the hub, a plurality of units comprising two integral blades having a common boss with a cam shoulder, said hub being provided with recesses to allow the blades to be alternately positioned in substantial parallelism with the hub axis, said boss being pivotally mounted in said hub, said blades being set relatively to each other at substantially a right angle and with relative pitches to produce in one a forward thrusting motion and in the other a reverse thrusting motion, a reciprocable cup-shaped member contained in said hub, a coil spring contained in said member and positioned to exert tension thereon, a removable cap with vents for the nose of the hub to allow access to said member and spring, and a longitudinal control rod secured to the base of said cup-shaped member and passing through the propeller shaft, said member abutting said cam shoulder and actuating same when the rod is operated to pivot said blades alternately out of operative position.

3. A propeller comprising a rotatable hub, a pair of blades connected for movement together, said pair of blades having a projecting lug, a common pivot for said pair of blades extending transversely of said hub, said blades being oppositely pitched to exert forward and rearward thrusts, respectively, and being angularly spaced from each other, said hub being provided with means for causing said pair of blades to normally occupy a position in which one of the blades lies along

said hub in an inoperative position and the other blade extends radially from the hub in an operative position, and operating means for moving said pair of blades from said normal position to a position in which said one blade extends radially from said hub and said other blade lies along said hub, said operating means including spring means acting upon said lug in one direction and other means operating upon said spring means in an opposite direction.

4. A propeller comprising a rotatable hub, a pair of blades connected for movement together, said pair of blades having a projecting lug, a common pivot for said pair of blades extending transversely of said hub, said blades being oppositely pitched to exert forward and rearward thrusts, respectively, and being angularly spaced from each other, said hub being provided with means for causing said pair of blades to normally occupy a position in which one of the blades lies along said hub in an inoperative position and the other blade extends radially from the hub in an operative position, and operating means for moving said pair of blades from said normal position to a position in which said one blade extends radially from said hub and said other blade lies along said hub, said operating means including spring means acting upon said lug in one direction and a longitudinally movable element extending axially through said hub operating upon said spring means in an opposite direction.
